UNITED STATES PATENT OFFICE.

HOMER O. FISHER, OF CHICAGO, ILLINOIS.

BOTTLE-FILLER.

1,036,478.

Specification of Letters Patent. Patented Aug. 20, 1912.

Application filed April 28, 1911. Serial No. 623,812.

To all whom it may concern:

Be it known that I, HOMER O. FISHER, a citizen of the United States, residing at Chicago, in the county of Cook and State of Illinois, have invented certain new and useful Improvements in Bottle-Fillers, of which the following is a specification.

This invention relates to bottle fillers and refers more particularly to an improved 10 valve construction for bottle fillers.

One of the objects of the invention is to provide a valve which will positively regulate the level of the fluid supplied to the bottle, one which will keep the bottle from 15 being filled too full and prevent any waste of the fluid.

Another object is generally to improve the construction of the type of valve which is used for filling wide-mouthed bottles, such 20 as milk bottles.

In the accompanying drawings, Figure 1 is a fragmental side elevation of a bottle-filling machine equipped with a valve embodying my invention. Fig. 2 is a longitudinal sectional view through the valve and a portion of the tank, and showing the valve open. Fig. 3 is a fragmentary side elevation of the lower portion of the valve structure partially in section, showing the 25 bottle filled as full as is possible with the parts in this position, the check valve being closed. Fig. 4 is a fragmentary plan view of the tank and the valve. Fig. 5 is a sectional view through the lower portion of the valve structure taken in the plane of line 5—5 of Fig. 2. Fig. 6 is a view of the lower end 30 of the check valve head.

The bottle-filling machine to which my invention is applied may be of any suitable 40 construction, being herein shown as comprising a supporting frame 10 having a tank 11 in its upper portion adapted to contain a quantity of milk or other fluid. Vertically slidable in the frame 10 is a platform 12 adapted to support one or more bottles *a* or a case *b* of bottles. The platform 12 may be moved in any common or preferred way, as by means of a hand lever 13 connected to 45 said platform through the medium of a link 14.

The tank 11 may be provided with a plurality of valves embodying my invention adapted to supply milk to a single row or the entire number of bottles, as desired, in 55 the case *b*. One of the valves is illustrated in Fig. 2 and comprises a tube 15 having its

upper end rigidly secured in the lower wall 16 of the tank 11 in any suitable way. Herein I have shown the upper end of the tube 15 fitting within an annular nut or bushing 17 which is threaded in an opening 18 in the lower wall 16 of the tank 11.

Surrounding the tube 15 and slidable thereupon is a sleeve 19, which sleeve is normally pressed downwardly by a coiled 60 spring 20 surrounding said sleeve and the tube 15, said spring bearing at its upper end against the bushing 17 and at its lower end against a ring 21 which fits about and is secured to the sleeve 19 near its lower end. 65 A suitable closure or stopper 22 which is preferably formed of rubber fits upon the lower end of the sleeve 19 and is adapted to tightly close the mouth of the bottle *a*.

Milk from the tank 11 flows downwardly 70 through the tube 15 and escapes through openings 23 formed in the side walls of said tube near its lower end. The flow of milk through said openings is controlled by the sleeve 19 which is adapted to blank or close 75 said openings. The lower end 15^a of the filling tube beneath the openings 23 constitutes a liquid-displacing body which is normally telescoped into the sleeve 19, the purpose of which will be later described.

The air in the bottle *a* escapes through a vent pipe 24 positioned within the milk tube 15 and extending upwardly through the tank 11 to a point above the level of the milk therein. The lower end of the vent 80 pipe 24 has a hollow head 25 fixed thereon, which head is arranged to close the lower end of the milk tube 15, a fluid tight joint being formed between said head and said tube by a gasket 26. The head 25 is normally held in position to close the tube 15 by means of leaf springs 27 fixed to the vent pipe 24 within the tank 11, the lower diverging portions of said leaf springs being adapted to rest upon an annular shoulder 85 28 which is formed by the upper end of the milk tube 15 and an annular recess 29 in the bushing 17. The springs 27 may be pressed toward the vent pipe 24 to withdraw them from the shoulder 28 and permit the 90 vent pipe to be withdrawn downwardly out of the milk tube 15 when it is desirable to wash the parts of the valve. After the vent pipe 24 and head 25 have been removed the sleeve 19 and spring 20 may be withdrawn 95 100 from the milk tube 15 so that all of the parts may be cleansed.

105

The head 25 has a chamber 30 therein communicating with the vent pipe 24, said head having a plurality of openings 31 extending from said chamber to the exterior 5 surface of the head. Within the chamber 30 is a member 32 of specific gravity less than the liquid to be bottled, preferably a wooden ball, which forms a check valve adapted to close the lower end of the vent 10 pipe 24 when the milk rises to a height in the bottle sufficient to float the ball 32, as shown in Fig. 3.

The operation of my improved filler is as follows: Relative movement to open the 15 valve may be had either by raising the bottles *a* or by lowering the tank 11, as will be readily understood. Herein I have shown means for raising the bottles *a*, and when one of these bottles comes in contact with 20 the closure 22 the sleeve 19 is slid upwardly along the milk tube 15 to uncover the outlet openings 23 and permit milk to descend from the tank 11 through the tube 15 and into the bottle *a*. As will be seen, the milk 25 escaping from the openings 23 comes in contact with the side walls of the bottle *a* and follows said walls downwardly so that the milk flows into the bottle quietly and substantially without frothing. The air in the 30 bottle displaced by the incoming milk escapes through the vent pipe 24. When the milk in the bottle rises to a sufficient height to float the ball or valve member 32, said ball rises upon the surface of the milk and 35 is carried into position to close the lower end of the vent pipe 24 and thus prevent milk from rising in said vent pipe. In this position of the valve 32, air cannot escape through the vent pipe, and as the milk continues 40 flowing in through the openings 23 the air bubbles up through the tube 15 and escapes from the surface of the milk in the tank 11. When the level of the milk has risen to the point indicated in Fig. 3, the 45 inflow of milk will cease. The bottle may now be lowered by the operator, the sleeve 19 following the bottle downwardly and blanking the openings 23. During the time the sleeve 19 is thus blanking said openings 50 23 a sufficient quantity of milk enters the bottle through said openings to raise the level of the liquid from that shown in Fig. 3, nearly to the top of the bottle, the milk subsiding to the desired or predetermined 55 height in the bottle to take the place occupied by the lower portion of the valve structure after the bottle has been fully withdrawn away from the valve.

As will be seen, the check valve structure 60 25-32 serves to positively prevent milk from rising in the vent pipe 24. In previous constructions, unless the bottle were withdrawn at the proper time when the desired amount of milk has been filled there- 65 in, the milk would rise in the vent pipe 24

to a greater or less height and finally, if permitted, to the level of the liquid in the tank 11. Then, when the bottle was lowered away from the valve, all of the milk in the vent pipe 24 would flow into the bottle and perhaps fill it to a higher level than desirable, or cause a waste of the milk after the bottle is withdrawn. My invention entirely obviates this difficulty. 70

The parts of the valve are easily disassembled when it is desired to clean said parts, by merely pressing together the lower ends of the leaf springs 27, when all of the removable parts may be withdrawn from the tank. 75

In milk-bottle filling valves as heretofore constructed, the flow of milk has not been shut off until about the moment when the valve parts reached the initial position. When it is remembered that the inflow of milk continues while the bottle and the valve are being separated, it will be seen that, with the prior construction just referred to, filling of the bottle to an excessive height could only be prevented by constructing the parts below the mouth-contacting member or stopper relatively large so as to displace a considerable quantity of milk, and thus make room for the milk that will descend into the bottle from the vent pipe. In filling cased bottles, it frequently happens that the bottles in a given case are not filled uniformly, and in such event the operator returns the case of bottles into filling relation with the valves. When properly-filled bottles are so returned to valves of the prior construction above alluded to, the parts below the mouth-contacting member displace some of the milk. The milk thus displaced is not only wasted, but also necessitates the rinsing of the exteriors of the bottles after the latter have been capped. I obviate these difficulties by constructing the valve so that the parts below the stopper, when in initial position, are of little volume and 100 displace but little milk; and also by forming the outlet openings 23 at some distance above the lower end of the tube 15, so that the portion of the milk tube below said opening forms a milk-displacing body, 105 which remains in its position in the milk subsequent to the closing of the opening 23 in the downward movement of the sleeve 19. Thus after the bottle has been originally filled, as the bottle is withdrawn from the 110 valve the openings 23 are first closed and then the said milk-displacing body is telescoped into the sleeve 19, leaving only the chambered head 25 in the milk before the bottle is finally withdrawn from the closure 115 22. Thus it will be seen that when a case of full bottles is returned to the valve those of the bottles which are already properly filled will be closed by the closure 22 at a time when only the chambered head 25 pro- 120 125 130

jects into the milk, said head displacing only a little milk and not enough to overflow the bottle. As the bottles are raised farther the sleeve 19 is carried up to uncover the lower portion of the tube 15 and finally open the outlet openings 23 to let milk flow into those of the bottles which are not already filled. As before explained, when the bottles are withdrawn from the 10 valve, the milk therein subsides to the desired height, the flow of milk having been cut off before the lower end of the tube 15 is telescoped into the sleeve 19.

I claim as my invention:

15 1. A valve structure for bottle fillers, comprising a filling tube, a chambered head closing the lower end of said tube, a vent pipe within said tube and having its lower end mounted in said head, a buoyant ball 20 arranged to close the lower end of said vent pipe, said filling tube having outlet openings in its side at a distance above its lower end, and a sleeve slidable on said tube and arranged to close said outlet openings, the 25 portion of said tube below said outlet openings forming a liquid-displacing body which is normally telescoped into said sleeve, said head being of a volume to displace only a relatively small volume of milk.

30 2. In a valve structure for bottle fillers, the combination of a filling tube; means including a sleeve slidable on said tube for controlling the discharge of liquid therefrom; a portion at the lower end of said tube 35 and beneath the point of discharge therefrom, said portion constituting a liquid displacing body and being normally telescoped into said sleeve; a vent pipe within said tube, and a floatable valve member arranged 40 to be raised by the liquid in the bottle to close the lower end of said vent pipe and prevent the entrance of any liquid into said pipe.

3. A valve structure for bottle fillers comprising a filling tube, a vent pipe within said tube, a chambered head with which the lower end of said pipe communicates, said head during use being fixed to said lower end of the vent pipe and being permanently 50 held in position to close the lower end of said filling tube, said head and vent pipe being removable for cleaning purposes from the filling tube, the latter having an outlet opening in its side, means controlling the 55 flow of liquid through said outlet opening, and a valve member within said head and movable by the rising liquid in the bottle into position to close the lower end of said vent pipe and prevent the entrance of liquid 60 into said vent pipe.

4. In a valve structure for bottle fillers, the combination of a filling tube; means including a sleeve slidable on said tube for controlling the discharge of liquid therefrom; a portion at the lower end of said

tube and beneath the point of discharge therefrom; said portion constituting a liquid-displacing body, and being normally telescoped into said sleeve; a vent pipe within said filling tube; a member below said portion, said member being of a volume to displace only a relatively small quantity of milk; and a valve carried by said member, said valve being arranged to be floated upwardly by the rising liquid in the bottle to 70 cut off communication between the bottle and the lower end of said vent pipe and prevent the entrance of any liquid in said vent pipe.

5. A valve structure for bottle fillers comprising a filling tube having openings in its wall near the lower end of the tube, a sleeve slidable on said tube and arranged to close said openings, a vent pipe within said tube, a head permanently held in position 80 to close the lower end of said filling tube, the portion of said tube beneath said openings constituting a liquid displacing body which is normally telescoped into said sleeve, said head in its normal position projecting 85 beyond said sleeve and being of a volume to displace only a small quantity of liquid, and a buoyant valve member supported by said head and arranged to be raised by the rising liquid in the bottle into position to cut 90 off communication between the interior of the bottle and the lower end of said vent pipe to prevent the entrance of any liquid 95 into said vent pipe.

6. A bottle filling machine comprising a 100 tank, a filling tube having its upper end fixed in the bottom wall of said tank, a vent pipe within said filling tube, a chambered head fixed to the lower end of said vent pipe, and communicating therewith and closing 105 the lower end of said filling tube, releasable locking means engaging said vent pipe and a stationary part carried by said tank for permanently maintaining said head in its closing position during use, said filling tube 110 having openings in its side adjacent the lower end of the tube, a sleeve slidable on said tube and arranged to close said openings, a coiled spring surrounding said sleeve and said filling tube and arranged to 115 hold said sleeve in its lowermost position, a bottle stopper carried by the lower end of said sleeve, and a buoyant ball within said chambered head arranged to be lifted by the rising liquid in the bottle into position 120 to close the lower end of said vent pipe for the purpose described.

7. In a valve structure for bottle fillers, the combination of a filling tube, means including a sleeve fitting slidably upon said tube for controlling the discharge of liquid therefrom, a liquid-displacing body positioned below the point of discharge from said filling tube, said body being telescoped into the lower end of said sleeve when the 125

4
valve is closed, whereby when a bottle is moved into engagement with the valve structure to open the same, said liquid displacing body will be projected into the mouth of the bottle before the valve is open, a vent pipe within said filling tube, and a buoyant valve member arranged to be lifted by the rising liquid in the bottle to positively close

the lower end of said vent pipe and prevent any liquid from rising into said pipe. 10

In testimony, whereof I affix my signature in presence of two witnesses.

HOMER O. FISHER.
